UNITED STATES PATENT OFFICE

2,046,814

APPLIANCE FOR AIDING SCALP
TREATMENT

Edward J. Dykeman, Richmond, Ind.

Application February 8, 1935, Serial No. 5,640

2 Claims. (Cl. 128—163)

This invention relates to appliances which are used to aid in massaging the scalp, and thereby discouraging the formation of dandruff and other scalp impairments, and for promoting the growth of the hair. My invention is for use around the head, and while being used, distends the walls of the arteries, veins and capillaries which lead to the least nourished area of the scalp, thereby exercising the muscles and increasing the amount 10 of blood supply to that portion of the head necessary to the proper hair growth and development.

One of the principal objects of my invention is the provision of an appliance which is practical, 15 efficient, which is very cheaply manufactured, and which is very simple in its operation and utilization.

Other objects and advantages of my invention will suggest themselves in the course of the following description, and that which is new and useful will be set forth in the appended claims.

The preferred means for carrying out the principles of my invention in a practical, efficient, and comprehensive manner is shown in the accompanying drawing, in which—

Figure 1 is a pictorial illustration showing the application of my appliance.

Figure 2 is a plan view of my appliance.

Figure 3 is a detail cross section taken on line 30 3—3 of Figure 2.

Figure 4 is an elevation of the contracting mechanism of my appliance.

Figure 5 is a plan view of the contracting mechanism taken from line 5—5 of Figure 4.

Figure 6 is a detail sectional view taken on line 35 6—6 of Figure 4.

Figure 7 is a detail sectional view taken on line 7—7 of Figure 4.

Figure 8 is a detail sectional view taken on line 40 8—8 of Figure 4.

Figure 9 is a detail elevation taken from line 9—9 of Figure 4.

Figure 10 is a detail sectional view taken on line 45 10—10 of Figure 5.

Figure 11 is a detail sectional view taken on line 11—11 of Figure 6.

In order to make clear the details of my invention and the construction thereof, I will now set forth the same as fully and as comprehensively as I may, but it is to be understood that the construction which I show and describe may be slightly modified without departing from the spirit of my invention.

Similar indices designate like parts throughout 50 the several views.

The numeral 1 designates a metallic band which is formed from a length of metal. The band 1 has its end portion 1' secured by the rivet 2 to the adjusting rod 3, and has its end portion 1'' projecting through the aperture 4' in the ferrule 4. The end portion 1'' is secured to the block 5 by means of the screws 6 which are threaded into the block 5.

The numeral 7 designates a rubber tube which entirely encircles the major portion of the band 1. 10 The tube 7 is secured at its end portion 7' by means of the clamping action of the band 1 against the block 5 by the screws 6. A metal guard 8 is secured on the opposite end of the tube 7 to prevent damage to the end of the tube 15 when the same is drawn into contact with the ferrule 4. The tube 7 has the slots 7'', as shown in Figure 9, formed therein and providing means of access to the heads of the screws 6.

The block 5 is formed with its lower side concave in shape, and having a channeled slot 5^a formed longitudinally in its upper surface, said slot 5^a being for the reception of the adjusting rod 3. At one end of the block 5 is the enlarged portion 5' through which the aperture 5^b is 20 formed, the same being in alignment with the channeled slot 5^a. At the rear end of the enlarged portion 5', and rigidly secured thereto, is the ferrule 5''. At the forward end of the block 5 is the ferrule 4, which is rigidly secured 25 to block 5. The upper portion of the ferrule 4 has an aperture formed therein which allows the end 1' of the band 1, and the forward end portion of the adjusting rod 3 to pass freely therethrough. The lower portion of the ferrule 4 has the elongated aperture formed therein, and which normally positions the end 1'' of the band 1. 30

The major portion of the adjusting rod 3 is threaded for the wing-nut 9. The outer end of the adjusting rod 3 has the knob 10 rigidly secured thereto which provides a smooth end for the rod 3 and also prevents the wing-nut 9 from becoming disengaged from the rod 3. The inner end of the adjusting rod 3 has a slot formed 35 therein for the reception of the end 1' of the band 1. Also formed through the rod 3, near its inner end, is an aperture through which the rivet 2 extends, thereby rigidly connecting the band 1 with the adjusting rod 3.

The operation and utilization of my appliance 40 is substantially as follows:

The wing-nut 9 is turned so as to permit a sufficient length of the adjusting rod 3 to extend inwardly, thereby increasing the diameter of the circle formed by the band 1 so that the band may 45

be drawn downwardly over a person's head to the position as shown in Figure 1. The wing-nut 9 is then tightened against the ferrule 5" until the band fits the head very tightly. When 5 the band is drawn tightly about the head, the blood supply in the veins, arteries, and capillaries causes the walls thereof to become distended, thus causing the pressure of the blood to be greatly increased. After the blood supply is sufficiently 10 increased, the scalp may be massaged with the finger tips or a massage device, thereby invigorating the scalp. My appliance is not to be retained on the patient's head for a great length of time, but only long enough to massage the 15 scalp thoroughly, after which the wing-nut 9 is loosened, and the band removed from the patient's head.

Having now fully shown and described my invention, what I claim, and desire to secure by 20 Letters Patent of the United States, is—

1. An appliance to aid in exercising and restoring the functions to the arteries and veins of the scalp, comprising in combination, a block having a concave side and having a channelled 25 slot formed in the opposite edge and extending longitudinally thereof with the slot terminating

in an aperture formed in said block, a metal band having one of its ends rigidly secured to the concave surface of said block and having the opposite end thereof rigidly secured to one end of a threaded rod which extends longitudinally of the 5 channelled slot and through the aperture which is formed in said block, means for adjusting the circumference of said band, and a rubber tube encircling the major portion of said metal band, all substantially as shown and described. 10

2. An appliance to aid in restoring the functions to the arteries of the human head, comprising in combination, a metallic band, a rubber tube encircling the major portion of the metallic band, a block member having a channelled slot formed 15 longitudinally in one edge thereof, an enlarged portion formed integral with one end of said block member and with an aperture formed through said enlarged portion and forming a continuation of the channelled slot, a concave 20 surface formed in one side of said block member, means for rigidly securing one end of said metallic band to the concave surface of said block member, and means for adjusting said band with relation to a human head. 25

EDWARD J. DYKEMAN.
